LIGHTER

Jean Genoud, Lyon, France, assignor to Etablissements Genoud & Cie, Venissieux (Rhône), France

Filed Nov. 17, 1964, Ser. No. 82,645

Claims priority, application France May 28, 1963

Term of patent 7 years

(Cl. D48—27)

FIG. 3 is stippled to indicate contrast. The dominant features of my design reside in the portion shown in full lines, which portions are characterized by the appearance of the rear panel and thumb lever piece as best indicated in FIGS. 1, 3, and 6.

This is a continuation-in-part of my early application, Ser. No. D. 77,278, filed Nov. 1, 1963, and now abandoned.

I claim:

The ornamental design for a lighter, as shown and described.
